(57) **CLAIM**

The ornamental design for an odor control cartridge, as shown and described.

DESCRIPTION

FIG. 1 is an isometric view showing a first embodiment of an odor control cartridge design;

FIG. 2 is a top plan view of the odor control cartridge design of FIG. 1;

FIG. 3 is an elevated front view of the odor control cartridge design of FIG. 1;

FIG. 4 is an elevated right side view of the odor control cartridge design of FIG. 1;

FIG. 5 is a top plan view of a second embodiment of an odor control cartridge design, wherein an isometric view, an elevated front view and an elevated right side view are represented in FIGS. 1, 3 and 4 respectively;

FIG. 6 is an isometric view showing a third embodiment of an odor control cartridge design;

FIG. 7 is a top plan view of the odor control cartridge design of FIG. 6;

FIG. 8 is an elevated front view of the odor control cartridge design of FIG. 6;

FIG. 9 is an elevated right side view of the odor control cartridge design of FIG. 6; and,

FIG. 10 is a top plan view of a fourth embodiment of an odor control cartridge design, wherein an isometric view, an elevated front view and an elevated right side view are represented in FIGS. 6, 8 and 9 respectively.
